UNITED STATES PATENT OFFICE.

RANSOM Y. BOVEE, OF DENVER, COLORADO.

INTERNAL-COMBUSTION PRESSURE-PUMP.

1,105,747.

Specification of Letters Patent.

Patented Aug. 4, 1914.

Application filed December 26, 1912. Serial No. 738,663.

To all whom it may concern:

Be it known that I, RANSOM Y. BOVEE, a citizen of the United States, residing at Denver, in the county of Denver and State of Colorado, have invented certain new and useful Improvements in Internal-Combustion Pressure-Pumps, of which the following is a specification.

My invention relates to an internal combustion pressure pump and its principal object resides in the provision of a simple mechanism which is operated by the expansive force of an ignited charge of gaseous fluid, periodically delivered thereto from a suitable source of supply, and which by the same force exerted upon the surface of a body of water, will raise the same to a determinate elevation.

My invention is particularly adapted for use in pumping water from a well or other subterranean source, and its construction is such that after the mechanism has been initially started, its subsequent operation is substantially automatic as long as the supply of gaseous fluid continues. Several adjustments are provided to regulate the movements of the operative parts of the pump, the frequency of the explosions and the admission of expansive gases to the water to be raised, in accordance with varying circumstances and the height at which the water is discharged above its natural level, and an automatic lubrication system supplies the contacting surfaces of the operative parts of the pump with the lubricant necessary to reduce friction.

The above and other objects which will be fully brought out in the following description, I attain by the mechanism shown in the accompanying drawings, in the various views of which like parts are similarly designated and in which,

Figure 1 represents a fragmentary elevation of my internal combustion pressure pump. Fig. 2, a fragmentary, longitudinal section of the lower portion of the cylinder comprised in its construction and subjacent parts. Fig. 3, a fragmentary, longitudinal section of the upper portion of the cylinder. Fig. 4, a section taken along the line 4—4, Fig. 2. Fig. 5, a section along the line 5—5, Fig. 2, and Fig. 6, an enlarged, sectional view of the upper portion of the stuffing box on the upper cylinder head, showing the circuit closer which automatically times the ignition of the charges of the explosive fluid,

and the valves employed to regulate the cushion which checks the upward motion of the piston, and Fig. 7, a section taken along the line 7—7, Fig. 3.

Referring more specifically to the drawings, the reference numeral 2 designates an upright, hollow cylinder closed at its opposite ends by means of two heads 3 and 4, the upper one of which is provided with an integral stuffing-box 5 in which the hollow rod 6 of a piston 7 is slidably fitted. The bore of the box 5 is enlarged at its outer end to receive the packing 8 and the vertically adjustable gland 9, and the same is enlarged at its inner extremity to provide an annular compression chamber 10 for the reception of a plunger 12 of corresponding diameter which is formed integral with the piston 7 above the upper surface of the same.

Two check valves 13 and 14 applied in separate compartments of a common housing 15 which is secured in an opening in the wall of the chamber 10, are constructed to respectively permit the outflow and inflow of gases from and into the same. The egress valve 13 is composed of a ball which is normally seated by automatic pressure and a screw valve 16 is provided to regulate by its position relative to a seat in the housing 15, the flow of fluid from the opening controlled by the ball valve. The conical ingress valve 14 is normally maintained upon its seat by means of a spring 17 which being coiled around the exterior, threaded portion of its stem, is disposed between a screw cap on the valve housing and a nut which is screwed onto the extremity of the said stem to regulate the degree of pressure by which the inflow of air into the compression chamber is opposed.

A lubricator 18 has a spout 19 which connects with an opening in the wall of the chamber 10 to supply oil to a plurality of retaining grooves formed in its interior surface, and the same lubricator which is secured upon the cylinder head 4, communicates with a circular groove 20 which is formed in the flange at the upper end of the cylinder upon which the said head is supported and which has a plurality of ports through which the lubricant is conducted to the interior surface of the cylinder.

The piston 7 which is slidably fitted in the cylinder and provided with the usual packing rings, has a central chamber 21 which communicates with the hollow piston rod

and which is closed by means of a housing which is secured upon a central extension of the piston in spaced relation to the lower surface of the same. This housing is composed of a body portion 22 and a cover 22^a which is screwed upon the lower end thereof and it is provided in its upper portion with a plurality of segmental ports 23 which are aligned with similar ports 24 in the body portion of the piston.

5 A disk valve 31 controls in the operation of the pump, the flow of gases between the portions of the cylinder at opposite sides of the piston and between the interior of the cylinder and the chamber 21, and it is by means of a yoke 25 and studs 32, secured at the lower extremity of a rod 26 which extends through the piston rod 6.

10 A cap 27 which is secured at the upper end of the hollow piston rod has in its upper surface, an opening through which the rod 26 extends. A valve 28 is supported upon the said surface to normally close the said opening, and a coiled spring 29 is disposed between a nut 30 on the rod and a bushing in the valve 28 for the purpose of holding the valve 31 in its normal position in which the ports 24 of the piston 7 are closed. A standard 33 on the cap 27, carries at its upper end, a rotary cam 34 which is adapted to move the rod 26 longitudinally by engagement with the upper end thereof for the purpose of lowering the valve 31 to uncover the ports 24.

15 A carbureter 35 which connects with a gas-supply tank 36, is connected with the interior of the cylinder 2 by means of a conduit 37, and a check valve 38 is applied to the said conduit for the purpose of preventing the return-flow of gases from the cylinder.

20 During each downward movement of the piston 7, a charge of gases is drawn from the carbureter into the cylinder and is at a determinate point in the said movement, ignited by means of a spark plug 39 which is disposed in an opening of the conduit 37 and whose separated contacts are connected at opposite sides of a break in a normally open electric circuit which includes a battery or spark coil disposed in a conveniently located box 40.

25 The means by which the circuit is periodically closed to cause a spark to traverse the space between the contacts of the plug, consist of a contact blade 41 which is mounted upon the cylinder head 4 in insulated relation thereto as is best shown in Fig. 6, and a block 42 which is clamped around the piston rod and which has two legs 43, one of which is disposed to engage the blade 41 during downward movement of the piston, the said blade and the said clamp being connected at opposite sides of a break in the electric circuit.

30 The block 42 limits the downward movement of the piston 7, by the engagement of its legs 43 with the upper surface of the stuffing box 5. Guide rods 44 which are erected on the stuffing box extend loosely through diametrically opposite bores in the block 42 and coiled cushion springs 45 are secured at the upper ends of the said guide rods to be engaged by the clamp 42 at the termination of the upward movement of the piston. The rods 44 also serve as a medium for the adjustment of the gland 9 whose flange has, to this end, been provided with openings through which the rods loosely extend, and whose upward displacement is prevented by the engagement of two stop nuts 46 which are screwed upon the threaded lower portions of the rods. The block is furthermore provided with two opposite laterally projecting handles 47, best shown in Fig. 7, which afford a convenient means for raising the piston when the pump is started at the beginning of its operation.

35 The portion of the pump which extends into the well or other source of water supply, includes an exterior casing 48 which, in axial alignment with the cylinder, is connected at its upper extremity with a mantle 49 which surrounds the latter in spaced relation to its exterior surface and which at its upper end has an outlet conduit 50 through which the raised water is discharged from the pump. The mantle 49 besides constituting a part of the discharge conduit in which the water displaced by the action of the pump, is raised, provides a water jacket 90 which absorbs the heat generated in the cylinder by the periodical explosions of the gaseous mixture. The lower portion of the casing 48 is perforated to admit the water 95 in which it is immersed, to its interior, and to exclude rock, sand and other solids, and the casing has at a point of higher elevation, an interiorly applied ring 51 which constitutes a ledge from which the two water 100 chambers required in the operation of the pump as will hereinafter be described, are suspended.

40 The two chambers above referred to are provided by two concentric cylinders 52 and 53 which are connected at their upper ends by an annular head 54 which surrounds the upper, open end of the inner cylinder and closes the corresponding extremity of the outer one.

45 The head 54 has a surrounding flange 115 which rests upon a rubber gasket placed upon the ring 51 in the casing and it has two openings in which are secured, two conduits 55 and 56 of different diameters which at 120 their opposite ends, project through stuffing boxes in the lower head 3 of the cylinder. The larger one, 55, of the two conduits terminates in the upper portion of the exterior chamber 53, the other conduit extends down- 125

wardly through the said chamber and terminates below the same in the lower portion of the surrounding casing and the two conduits are provided with valves 57 and 58 5 which control the flow of gaseous fluid therethrough and whose stems project through stuffing boxes on the casing 48.

The lower extremity of the inner chamber 52 flares outwardly and is provided at a 10 point above the lower end of the outer chamber with an annular valve seat 59 upon which a foot valve 60 is loosely supported, and a similar valve seat 61 applied at the extremity of the outer chamber is provided 15 to support a correspondingly formed valve 62. The valves are guided during their up and downward motion by means of pins 63 and 64 which being secured upon central portions of the valve seats, extend 20 loosely through openings in the respective valves and are provided at their upper ends with heads to limit the upward movement of the same.

In the operation of the pump, the casing 25 48 is lowered in the well or other source of water supply until the chambers 52 and 53 are entirely submerged. The upward flow of the water normally holds the foot valve 62 of the outer or receiving chamber elevated above its seat, while the weight of the water contained in the inner or discharge chamber 52 closes the foot valve 60 at the lower end thereof. To start the pump, the piston is raised by means of the handles 47 30 on the block 42 after the valve 31 has been lowered by means of the cam 34 to establish communication between the portions of the cylinder at opposite sides of the piston and to thus equalize the pressure of fluid 35 throughout the cylinder. After the cam has been returned to its original position, the piston on being released descends by gravity 40 and during its downward movement, draws a charge of gaseous mixture from the carburetor into the cylinder.

At the termination of the gravitational movement of the piston, which is determined by the engagement of the legs on the clamp 42 with the upper surface of the stuffing box on the upper cylinder head, the simultaneous closing of the electric circuit causes an electric spark to traverse the space 50 between the contacts of the spark plug, with the result that the charge of gases drawn 55 into the cylinder, is exploded. The consequent expansion of the gases in the cylinder lowers the valve 31 against the pressure of the spring 29 thereby closing the exhaust ports 23 and opening the ports 24 through 60 which the gases rush into the portion of the cylinder below the piston. The expansive fluid entering through the conduit 55 presses 65 upon the water contained in the receiving chamber 53 and drives it downwardly, thereby causing the foot valve 62 to close and the

valve 60 at the bottom of the inner chamber 52, to simultaneously open. The displaced water having no other means of escape, is thus driven upwardly through the chamber 52 and the therewith communicating upper portion of the discharge conduit 48, into the jacket around the cylinder from which it is discharged through the outlet 50.

When, by lowering of the valve 31, communication is established between the portions of the cylinder at opposite sides of the piston, the pressure of the expansive gases upon the lower piston surface whose area is by the closing of the exhaust ports 23, increased to exceed that of the upper surface, will drive the piston upwardly until its movement is arrested by the cushion of compressed gases in the chamber 10 into which the plunger 12 of the piston has entered, and the simultaneous engagement of the block 42 with the springs 45. When the piston has reached this position, the decrease in density of the gaseous fluid contained in the cylinder causes the valve 31 to move to its original position by expansion of the spring 29 whose tension has previously been regulated to slightly overbalance the weight of the piston. The gases which remained in the cylinder, the conduit 55, and the chamber 53 are exhausted through the hollow piston rod past the valve 28 which is raised by the upward flow of the same and as soon as the gases have left the cylinder, the said valve closes by gravitation and thus prevents air from entering the same. The cushion formed in the compression chamber of the head 4 is at the same time dissipated by the discharge of the gases past the check valve 13 and the space formerly occupied by the cushion is subsequently filled with air of atmospheric pressure which enters the chamber 10 past the check valve 14, the velocity with which this air flows into the said space, being determined by the pressure of the spring 17. 100

When the space in the annular chamber above the plunger 12 has thus been filled with air, the piston will, by reason of the partial vacuum existing in the portion of the cylinder below the same, descend by 115 gravity, a new supply of water will at the same time ascend in the receiving chamber, and the above described action is repeated. It will thus be observed that in the operation of the pump, a rapid reciprocating movement is automatically imparted to the piston as long as the supply of gases continues and that in consequence, water will be continuously discharged through the outlet 50 in a substantially uninterrupted 120 stream.

When an accumulation of sand or other solids below the chambers 52 and 53 threatens to interfere with the proper operation of the apparatus, the valve 57 in the con- 125

duit 55 is temporarily closed and that in the conduit 56, opened, whereby the gases are delivered from the cylinder into the lower portion of the casing 48 to drive the 5 obstructive matter upwardly through the chamber and the jacket to be discharged through the outlet 50.

In the ordinary operation of the pump the valve 57 in the conduit 55 is entirely or partially opened to regulate the downward flow 10 of gases in accordance with the resistance offered by the weight of the column of water to be raised, it being obviously essential that the pressure of gases below the piston remains at all times sufficient to drive the same 15 upward. The stroke of the piston may be varied in accordance with different circumstances by changing the position of the clamp 42 which limits the downward movement of the piston and determines the time 20 of ignition of the charge, on the piston rod.

The oiling system above explained, automatically supplies the oil to the contact surfaces of the moving parts to lessen friction 25 and when for the purpose of repairs or inspection, it is desired to remove the cylinder and the water chambers, it is but necessary to detach the upper cylinder head from the casing and remove the valves 57 and 58 30 which leaves the cylinder and the water chambers, free to be moved upwardly out of the casing 48 and the thereto attached mantle 49.

Having thus described my invention what 35 I claim and desire to secure by Letters-Patent is:

1. An internal combustion pressure pump comprising a cylinder having at its opposite ends, respectively, an inlet and an outlet for 40 gaseous fluid, a chamber in communication with said outlet and adapted to connect with a source of water-supply, a discharge conduit connected with said chamber, a piston having a reciprocating movement in the cylinder and provided with ports for establishing communication between the portions of the cylinder at opposite sides of the piston, a valve normally closing said ports and adapted to open the same by the explosion of fluid 50 in one of said portions, means for opening said ports, by manually adjusting the valve from a point outside the cylinder, and means for igniting a charge of explosive gases in said cylinder at a determinate point in the 55 movement of the piston.

2. An internal combustion pressure pump comprising a cylinder having at its opposite ends, respectively, an inlet and an outlet for 60 gaseous fluid, a chamber in communication with said outlet and adapted to connect with a source of water-supply, a discharge conduit connected with said chamber, a piston having a reciprocating movement in the cylinder and provided with ports for establishing 65 communication between the portions of

the cylinder at opposite sides of the piston, a hollow rod to which the piston is attached, a valve for controlling the flow of gases through said ports and from the interior of the cylinder into the said rod, a stem on said valve extending through said rod, a spring normally holding said valve to close the ports in the piston, and means for igniting a charge of explosive gases in the cylinder at 70 a determinate point in the movement of the 75 piston.

3. An internal combustion pressure pump comprising a cylinder having at its opposite ends, respectively, an inlet and an outlet for 80 gaseous fluid, a chamber in communication with said outlet and adapted to connect with a source of water-supply, a discharge conduit connected with said chamber, a piston having a reciprocating movement in the cylinder and provided with ports for establishing communication between the portions of the cylinder at opposite sides of the piston, a hollow rod attached at its inner end to the piston, a valve for controlling the flow of gases through said ports and from the 85 interior of the cylinder into said rod, a spring normally holding said valve to close the ports in the piston, a valve normally closing the outer end of said rod and adapted to open the same by a flow of gases 90 through the rod, and means for igniting a charge of explosive gases in the cylinder at 95 a determinate point in the movement of the piston.

4. An internal combustion pressure pump comprising a cylinder having at its opposite ends, respectively, an inlet and an outlet for 100 gaseous fluid, a chamber in communication with said outlet and adapted to connect with a source of water-supply, a discharge conduit connected with said chamber, a piston having a reciprocating movement in the cylinder and provided with ports for establishing communication between the portions of the cylinder at opposite sides of the piston, a hollow rod attached at its inner end to the piston, a valve for controlling the flow of gases through said ports and from the interior of the cylinder 105 into said rod, a stem on said valve extending through said rod, a spring normally holding said valve to close the ports in the piston, a cam on said rod adapted to displace the valve by engagement with said stem, and means for igniting a charge of 110 explosive gases in the cylinder at a determinate point in the movement of the piston.

5. In an internal combustion pressure pump, a cylinder having at one of its ends, an inlet for gases and a compression chamber, and at its opposite end, an outlet, a chamber in communication with said outlet and adapted to connect with a source of water-supply, a discharge conduit in communication with said chamber, a piston hav- 115 120 125 130

ing a reciprocating movement in the cylinder, means to establish communication between the portions of the latter at opposite sides of the piston by the explosion of fluid in one of said portions, said piston having a plunger adapted to enter said compression chamber for the formation of a gaseous cushion, a system for automatic lubrication of the surfaces of the cylinder and the compression chamber, and means for igniting a charge of explosive gases in said cylinder at a determinate point in the movement of the piston.

6. An internal combustion pressure pump comprising a cylinder having at its opposite ends, respectively, an inlet and an outlet for gaseous fluid, a chamber in communication with said outlet and adapted to connect with a source of water-supply, a discharge conduit in communication with said chamber, a piston having a reciprocating movement in said cylinder, means to establish communication between the portions of the cylinder at opposite sides of the piston by the explosion of fluid in one of said portions, a rod on said piston extending through an opening in the cylinder, a spark-plug in an electric circuit, and a circuit-closer normally breaking said circuit and comprising a contact secured to said rod, and a fixed contact disposed to be engaged by the first-mentioned contact at a determinate point in the stroke of the piston.

7. An internal combustion pressure pump comprising a cylinder having at its opposite ends, respectively, an inlet and an outlet for gaseous fluid, a chamber in communication with said outlet and adapted to connect with a source of water supply, a discharge conduit in communication with said chamber, a piston having a reciprocating movement in said cylinder, means to establish communication between the portions of the cylinder at opposite sides of the piston by the explosion of fluid in one of said portions, a rod on said piston extending through an opening in the cylinder, a spark-plug in an electric circuit, and a circuit-closer normally breaking said circuit and comprising a contact adjustably secured to said rod, and a fixed contact disposed to be engaged by the first-mentioned contact at a determinate point in the stroke of the piston.

8. An internal combustion pressure pump comprising a cylinder having at its opposite ends, respectively, an inlet and an outlet for gaseous fluid, a chamber in communication with said outlet and adapted to connect with a source of water supply, a discharge conduit in communication with said chamber, a piston having a reciprocating movement in said cylinder, means to establish communication between the portions of the cylinder at opposite sides of the piston by the explosion of fluid in one of said por-

tions, a rod on said piston extending through an opening in the cylinder, a spark-plug in an electric circuit, and a circuit-closer normally breaking said circuit and comprising a contact secured to said rod and adapted to limit the movement of the piston in one direction by engagement with a relatively stationary part, and a fixed contact disposed to be engaged by the first-mentioned contact at a determinate point in the stroke of the piston.

9. An internal combustion pressure pump comprising a cylinder having at its opposite ends, respectively, an inlet and an outlet for gaseous fluid, a chamber in communication with said outlet and adapted to connect with a source of water-supply, a discharge conduit in communication with said chamber, a piston having a reciprocating movement in said cylinder, means to establish communication between the portions of the cylinder at opposite sides of the piston by the explosion of fluid in one of said portions, a rod on said piston extending through an opening in the cylinder, means for igniting a charge of explosive gases in the cylinder at a determinate point in the movement of the piston, and a block secured to said rod for limiting the movement of the piston by engagement with a stationary part.

10. An internal combustion pressure pump comprising a cylinder having at its opposite ends, respectively, an inlet and an outlet for gaseous fluid, a chamber in communication with said outlet and adapted to connect with a source of water supply, a discharge conduit in communication with said chamber, a piston having a reciprocating movement in said cylinder, means to establish communication between the portions of the cylinder at opposite sides of the piston by the explosion of fluid in one of said portions, a rod on said piston extending through an opening in the cylinder, means for igniting a charge of explosive gases in the cylinder at a determinate point in the movement of the piston, guide rods on the cylinder, cushion springs on said rods, and a block movable on said rods and secured to the piston rod for limiting the movement of the piston by alternate engagement with the said springs and with a stationary part.

11. An internal combustion pressure pump comprising a cylinder having at its opposite ends, respectively, an inlet and an outlet for gaseous fluid, a chamber in communication with said outlet and adapted to connect with a source of water supply, a discharge conduit in communication with said chamber, a piston having a reciprocating movement in said cylinder, means to establish communication between the portion of the cylinder at opposite sides of the piston by the explosion of fluid in one of said por-

- tions, a rod on said piston extending through a stuffing box on said cylinder, means for igniting a charge of explosive gases in the cylinder at a determinate point in the movement of the piston, a gland in said stuffing box, a block secured to the piston rod, guide rods on said cylinder along which said gland and said block are movable, and springs on said guide-rods to be engaged by said 5 block at a determinate point in the movement of the piston.
12. An internal combustion pressure pump comprising a cylinder having at its opposite ends, respectively, an inlet and an outlet for 10 gaseous fluid, a piston having a reciprocating movement in said cylinder, means to establish communication between the portions of the cylinder at opposite sides of the piston by the explosion of fluid in one of 15 said portions, means for igniting a charge of explosive gases in said cylinder at a determinate point in the movement of the piston, a mantle forming a water-jacket around said cylinder, and a chamber in communication with said outlet and with said jacket and adapted to connect with a source of 20 water-supply.
13. An internal combustion pressure pump, comprising a cylinder having at one 25 of its ends, an inlet and at its opposite end, two outlets for gaseous fluid, a piston having a reciprocating movement in said cylinder, means to establish communication between the portions of the cylinder at opposite sides of the piston by the explosion of fluid in one of 30 said portions, means for igniting a charge of explosive gases in said cylinder at a determinate point in the movement of the piston, a chamber adapted to 35 connect with a source of water-supply, a discharge conduit connected with said chamber, and two valve-controlled conduits connected respectively with the outlets in the cylinder for the discharge of gases in the upper portion 40 of said chamber and at a point below the same.
14. An internal combustion pressure pump comprising a cylinder having at its opposite ends, respectively, an inlet and an outlet for 45 gaseous fluid, a piston having a reciprocating movement in said cylinder, means to establish communication between the portions of the cylinder at opposite sides of the piston by the explosion of fluid in one of 50 said portions, means for igniting a charge of explosive gases in said cylinder at a determinate point in the movement of the piston, a discharge conduit, a receiving chamber adapted to connect with a source of 55 water-supply and communicating with the outlet of the cylinder, a discharge chamber in communication with the receiving chamber and with the discharge conduit, and valves controlling the flow of water from the 60 source of supply into the receiving chamber, 65 and from the latter into the discharge chamber.
15. An internal combustion pressure pump comprising a cylinder having at its opposite ends, respectively, an inlet and an outlet for 70 gaseous fluid, a piston having a reciprocating movement in said cylinder, means to establish communication between the portions of the cylinder at opposite sides of the piston by the explosion of fluid in one of 75 said portions, means for igniting a charge of explosive gases in said cylinder at a determinate point in the movement of the piston, a discharge conduit, a receiving chamber adapted to connect with a source of water-supply and communicating with the outlet of the cylinder, a discharge chamber in communication with the receiving chamber and with the discharge conduit, one of 80 said chambers surrounding the other, and valves controlling the flow of water from the source of supply into the receiving chamber, and from the latter into the discharge chamber.
16. An internal combustion pressure pump comprising a cylinder having at its opposite ends, respectively, an inlet and an outlet for 85 gaseous fluid, a piston having a reciprocating movement in said cylinder, means to establish communication between the portions of the cylinder at opposite sides of the piston by the explosion of fluid in one of 90 said portions, means for igniting a charge of explosive gases in said cylinder at a determinate point in the movement of the piston, a discharge conduit, a discharge chamber in communication therewith, a receiving chamber communicating with the outlet of the cylinder and surrounding the discharge chamber, the lower extremity of the said receiving chamber being below the corresponding end of the discharge chamber, and valves controlling the flow of fluid into the lower ends of 95 said chambers.
17. An internal combustion pressure pump comprising a cylinder having at its 100 opposite ends, respectively, an inlet and an outlet for gaseous fluid, a piston having a reciprocating movement in said cylinder, means to establish communication between the portions of the cylinder at opposite sides of the piston by the explosion of fluid in one of 105 said portions, means for igniting a charge of explosive gases in said cylinder at a determinate point in the movement of the piston, a discharge conduit, a discharge chamber in communication therewith, a receiving chamber communicating with the outlet of the cylinder and surrounding the discharge chamber, the lower extremity of the said receiving chamber being below the corresponding end of the discharge chamber, and gravity valves controlling the flow of fluid into the lower ends of 110 said chambers.
18. An internal combustion pressure pump comprising a cylinder having at its 115 opposite ends, respectively, an inlet and an outlet for gaseous fluid, a piston having a reciprocating movement in said cylinder, means to establish communication between the portions of the cylinder at opposite sides of the piston by the explosion of fluid in one of 120 said portions, means for igniting a charge of explosive gases in said cylinder at a determinate point in the movement of the piston, a discharge conduit, a discharge chamber in communication therewith, a receiving chamber communicating with the outlet of the cylinder and surrounding the discharge chamber, the lower extremity of the said receiving chamber being below the corresponding end of the discharge chamber, and gravity valves controlling the flow of fluid into the lower ends of 125 said chambers.
19. An internal combustion pressure pump comprising a cylinder having at its 130 opposite ends, respectively, an inlet and an outlet for gaseous fluid, a piston having a reciprocating movement in said cylinder, means to establish communication between the portions of the cylinder at opposite sides of the piston by the explosion of fluid in one of

opposite ends, respectively, an inlet and an outlet for gaseous fluid, a piston having a reciprocating movement in said cylinder, means to establish communication between the portions of the cylinder at opposite sides of the piston by the explosion of fluid in one of said portions, means for igniting a charge of explosive gases in said cylinder at a determinate point in the movement of the piston, 5 a discharge-conduit, a receiving chamber adapted to connect with a source of water-supply, a conduit connected with the outlet of the cylinder and extending into the receiving chamber, a valve for controlling the 10 flow of fluid through said conduit, a discharge chamber in communication with the receiving chamber and with the discharge conduit, and valves controlling the flow of water from the source of supply into the receiving chamber and from the latter into the discharge chamber.

19. An internal combustion pressure pump comprising a cylinder at its opposite ends, respectively, an inlet and an outlet 25 for gaseous fluid, a piston having a reciprocating movement in said cylinder, means to establish communication between the portions of the cylinder at opposite sides of the piston by the explosion of fluid in one of said portions, means for igniting a charge 30 of explosive gases in said cylinder at a determinate point in the movement of the piston, an upright casing having a discharge opening in its upper portion and an inlet 35 for water at its lower end, a receiving chamber and a discharge chamber placed one within the other, within said casing, valves controlling the flow of water from said casing into said receiving chamber and from 40 the latter into the discharge chamber, and a conduit connecting the outlet of the cylinder with the receiving chamber.

20. An internal combustion pressure pump comprising a cylinder having at its 45 opposite ends, respectively, an inlet and an outlet for gaseous fluid, a piston having a reciprocating movement in said cylinder, means to establish communication between the portions of the cylinder at opposite sides 50 of the piston by the explosion of fluid in one of said portions, means for igniting a charge of explosive gases in said cylinder at a determinate point in the movement of the piston, a mantle forming a water jacket around 55 the cylinder and having an outlet, a casing connected with said jacket and having a water inlet at its lower end, a receiving chamber and a discharge chamber placed one within the other, within said casing, valves 60 controlling the flow of water from said casing into said receiving chamber and from the latter into the discharge chamber, and a conduit connecting the outlet of the cylinder with the receiving chamber.

21. An internal combustion pressure

75 pump comprising a cylinder having at one of its ends, an inlet and at its opposite end, two outlets for gaseous fluid, a piston having a reciprocating movement in said cylinder, means to establish communication between the portions of the cylinder at opposite sides of the piston by the explosion of fluid in one of said portions, means for igniting a charge of explosive gases in said cylinder at a determinate point in the movement of the piston, an upright casing having a discharge opening in its upper portion and an inlet for water at its lower end, a receiving chamber and a discharge chamber placed one within the other, within said casing, valves controlling the flow of water from said casing into said receiving chamber and from the latter into the discharge chamber, and conduits connected with the outlets of the cylinder and terminating respectively in the upper portion of the receiving chamber, and in the portion of the said casing below the said chambers.

22. An internal combustion pressure pump comprising a cylinder having at its opposite ends, respectively, an inlet and an outlet for 90 gaseous fluid, a piston having a reciprocating movement in said cylinder, means to establish communication between the portions of the cylinder at opposite sides of the piston by the explosion of fluid in one of said portions, means for igniting a charge of explosive gases in said cylinder at a determinate point in the movement of the piston, an upright casing having a discharge opening in its upper portion and an inlet for water at its lower end, a receiving chamber and a discharge chamber placed one within the other, loosely suspended within said casing, valves controlling the flow of water from 95 said casing into said receiving chamber and from the latter into the discharge chamber, and a conduit connecting the outlet of the cylinder with the receiving chamber.

23. An internal combustion pressure 110 pump comprising, an upright cylinder having at its upper end an inlet for gaseous fluid, and at its lower end an outlet for the same, a piston having a reciprocating movement in said cylinder and adapted to move 115 by gravity, means to establish communication between the portions of the cylinder at opposite sides of the piston by the explosion of fluid in the upper portion of the same, means for igniting a charge of explosive 120 gases in the said upper portion at a determinate point in the movement of the piston, a mantle forming a water jacket around said cylinder and having an outlet, a casing connected at the lower end of said mantle and 125 having a water-inlet at its lower end, a receiving chamber and a discharge chamber placed one within the other, within said casing, valves controlling the flow of water from said casing into said receiving chamber 130

and from the latter into the discharge chamber, and a conduit connecting the outlet of the cylinder with the receiving chamber.

24. An internal combustion pressure pump comprising a cylinder, a piston fitted for free reciprocation therein, said cylinder having at one side of the piston an inlet for gaseous fuel and at the opposite side of the same, an outlet for gases, a chamber in communication with said outlet and adapted to connect with a source of water-supply, a discharge conduit in communication with the said chamber, means for igniting at a determinate point in the movement of the piston in one direction, a charge of fuel drawn into the cylinder through its said inlet by the said movement of the piston, and means adapted to be operated by explosion of said charge caused by said ignition, to establish communication between the normally incommunicating parts of the cylinder at opposite sides of the piston, whereby the gases developed by the said explosion are admitted to the said outlet.

25. An internal combustion pressure pump comprising a cylinder, a piston fitted for reciprocation therein and provided with a port for the connection of the portions of the cylinder at opposite sides thereof, said cylinder having at one side of the piston, an inlet for gaseous fuel and at the opposite side of the same, an outlet for gases, a chamber in communication with said outlet, and adapted to connect with a source of water-supply, a discharge conduit in communication with the said chamber, means for igniting at a determinate point in the movement of the piston in one direction, a charge of fuel drawn into the cylinder through its side inlet by the said movement of the piston, and a valve normally closing the port in the piston and adapted to open the same by explosion of said charge caused by said ignition, to establish communication between the parts of the cylinder at opposite sides of the piston whereby the gases developed by the said explosion are admitted to the said outlet.

26. An internal combustion pressure pump comprising a cylinder, a piston fitted for free reciprocation therein, said cylinder having at one side of the piston an inlet for gaseous fuel and at the opposite side of the same, an outlet for gases, a chamber in communication with said outlet and adapted to connect with a source of water-supply, a discharge-conduit in communication with the said chamber, means for igniting at a determinate point in the movement of the piston in one direction, a charge of fuel drawn into the cylinder through its said inlet by the said movement of the piston, and means on said piston adapted to be operated by explosion of said charge caused by said ignition, to establish communication between

the normally incommunicating parts of the cylinder at opposite sides of the piston whereby the gases developed by the said explosion are admitted to the said outlet.

27. An internal combustion pressure pump comprising an upright cylinder, a differential piston fitted for reciprocation in said cylinder, free to move by gravitation, said cylinder having at one side of the piston an inlet for gaseous fuel, and at the opposite side of the same an outlet for gases, and the said piston having a port for the connection of the portions of the cylinder at opposite sides thereof, a hollow rod on the piston connecting with the outlet-portion of the cylinder for the discharge of gases therefrom at a point outside the cylinder, a check valve controlling the flow of gases through said rod, a chamber in communication with said outlet and adapted to connect with a source of water-supply, a discharge-conduit in communication with the said chamber, means for igniting at a determinate point in the downward movement of the piston, a charge of fuel drawn into the cylinder through its said inlet by the said movement of the piston, and a valve normally closing the port in the piston and adapted to open the same by an explosion of said charge caused by said ignition, to establish communication between the parts of the cylinder at opposite sides of the piston, whereby the gases developed by said explosion are admitted to said outlet and the respective side of the piston.

28. An internal combustion pressure-pump comprising a cylinder, a differential piston fitted for free reciprocation therein, said cylinder having at one side of the piston, an inlet for gaseous fuel and at the opposite side of the same, an outlet for gases, and the said piston having a port for the connection of the portions of the cylinder at opposite sides thereof, a hollow rod on the piston connecting with the outlet-portion of the cylinder for the discharge of gases therefrom at a point outside the cylinder, a check valve controlling the flow of gases through said rod, a chamber in communication with said outlet and adapted to connect with a source of water-supply, a discharge-conduit in communication with the said chamber, means for igniting at a determinate point in the movement of the piston in one direction, a charge of fuel drawn into the cylinder through its said inlet by the said movement of the piston, and a valve normally closing the port in the piston and adapted to open the same by an explosion of said charge caused by said ignition, to establish communication between the parts of the cylinder at opposite sides of the piston, whereby the gases developed by said explosion are admitted to said outlet and the respective side of the piston.

29. An internal combustion pressure pump comprising a cylinder, a piston fitted for reciprocation therein, and having a port to connect the portions of the cylinder at opposite sides thereof, said cylinder having at one side of the piston, an inlet for gaseous fuel, and a compression chamber, and at the opposite side of the same, an outlet for gases, a chamber in communication with said outlet and adapted to connect with a source of water-supply, a discharge-conduit in communication with the said chamber, means for igniting at a determinate point in the movement of the piston in one direction, a charge of fuel drawn into the cylinder by the movement of the piston in one direction, and a valve normally closing the port in the piston and adapted to open the same by an explosion of said charge caused by said ignition, to establish communication between the parts of the cylinder at opposite sides of the piston whereby the gases developed by said explosion are admitted to said outlet and the respective side of the piston, the said piston having a plunger adapted to enter said compression chamber at the end of its movement in the opposite direction for the formation of a gaseous cushion.
30. An internal combustion pressure pump comprising a cylinder, a piston fitted for reciprocation therein and having a port to connect the portions of the cylinder at opposite sides thereof, said cylinder having at one side of the piston, an inlet for gaseous fuel, a compression chamber, a valve to exhaust gases from the latter, and a valve to admit air into the same, and at the opposite side of the piston, and outlet for gases, a chamber in communication with said outlet and adapted to connect with a source of water-supply, a discharge conduit in communication with the said chamber, means for igniting at a determinate point in the movement of the piston in one direction, a charge of fuel drawn into the cylinder by the movement of the piston in one direction, and a valve normally closing the port in the piston and adapted to open the same by an explosion of said charge caused by said ignition, to establish communication between the parts of the cylinder at opposite sides of the piston whereby the gases developed by said explosion are admitted to said outlet and the respective side of the piston, the said piston having a plunger adapted to enter said compression chamber at the end of its movement in the opposite direction for the formation of a gaseous cushion.
31. An internal combustion pressure pump comprising an upright cylinder, a differential piston fitted for free reciprocation therein, and having a port for the connection of the portions of the cylinder at opposite sides thereof, said cylinder having at one side of the piston, an inlet for gaseous fuel, and a compression chamber and at the opposite side of the same, an outlet for gases, a hollow rod on the piston connecting with the outlet-portion of the cylinder for the discharge of gases therefrom at a point outside the same, a check-valve controlling the flow of gases through said rod, a chamber in communication with said outlet and adapted to connect with a source of water-supply, a discharge-conduit in communication with the said chamber, means for igniting at a determinate point in the downward movement of the piston, a charge of fuel drawn through its said inlet by the said movement of the piston, and a valve normally closing the port in the piston and adapted to open the same by an explosion of said charge caused by said ignition, to establish communication between the parts of the cylinder at opposite sides of the piston whereby the gases developed by said explosion are admitted to said outlet and the respective side of the piston, the said piston having a plunger adapted to enter said compression chamber at the end of its movement in the opposite direction for the formation of a gaseous cushion.
32. An internal combustion pressure pump comprising a cylinder, a differential piston fitted for free reciprocation therein, and having a port for the connection of the portions of the cylinder at opposite sides thereof, said cylinder having at one side of the piston an inlet for gaseous fuel and a compression chamber, and at the opposite side of the same, an outlet for gases, a hollow rod on the piston connecting with the outlet-portion of the cylinder for the discharge of gases therefrom at a point outside the same, a check valve controlling the flow of gases through said rod, a chamber in communication with said outlet and adapted to connect with a source of water-supply, a discharge-conduit in communication with the said chamber, means for igniting at a determinate point in the movement of the piston in one direction, a charge of fuel drawn through its said inlet by the said movement of the piston, and a valve normally closing the port in the piston and adapted to open the same by an explosion of said charge caused by said ignition, to establish communication between the parts of the cylinder at opposite sides of the piston whereby the gases developed by said explosion are admitted to said outlet and the respective side of the piston, the said piston having a plunger adapted to enter said compression-chamber at the end of its movement in the opposite direction for the formation of a gaseous cushion.
33. An internal combustion pressure pump comprising a cylinder, a piston fitted for free reciprocation therein, said cylinder having at one side of said piston, an inlet for

gaseous fuel and at the opposite side of the same, an outlet for gases, a water-chamber in communication with said outlet, and adapted for connection with a source of water supply, a discharge conduit in communication with the said chamber, means for igniting a charge of fuel drawn into the cylinder through its said inlet by the movement of the piston in one direction, at a determinate point in said movement, and means actuated by the explosion caused by said ignition for establishing communication between the parts of the cylinder at opposite sides of the piston, whereby to admit the gases developed by said explosion to the said outlet and to the respective side of the piston.

34. An internal combustion pressure pump comprising a cylinder, a piston fitted for free reciprocation therein, said cylinder having at one side of said piston an inlet for gaseous fuel and at the opposite side of the same, an outlet for gases, a water chamber in communication with said outlet and adapted for connection with a source of water-supply, a discharge conduit connected with said chamber, means for igniting a charge of fuel drawn into the cylinder through its said inlet by the movement of the piston in one direction, at a determinate point in said movement, means actuated by the explosion caused by said ignition for establishing communication between the parts of the cylinder at opposite sides of the piston, whereby to admit the gases developed by said explosion to the said outlet and

to the respective side of the piston, and means for the exhaust of gases from the outlet part of the cylinder during movement of the piston in the opposite direction. 40

35. An internal combustion pressure pump comprising a cylinder, a piston fitted for free reciprocation therein, said cylinder having at one side of said piston an inlet for gaseous fuel and at the opposite side of the same, an outlet for gases, a water chamber in communication with said outlet and adapted for connection with a source of water-supply, a discharge conduit connected with said chamber, means for igniting a charge of fuel drawn into the cylinder through its said inlet by the movement of the piston in one direction, at a determinate point in said movement, means actuated by the explosion caused by said ignition for establishing communication between the parts of the cylinder at opposite sides of the piston, whereby to admit the gases developed by said explosion to the said outlet and to the respective side of the piston, means for the exhaust of gases from the outlet part of the cylinder during movement of the piston in the opposite direction, and means for the discharge of gases compressed during the same movement of the piston in the other part of the cylinder. 45 50 55 60 65

In testimony whereof I have affixed my signature in presence of two witnesses.

RANSOM Y. BOVEE.
